RAILWAY SLEEPING CAR

Frank L. Murphy and James E. Candlin, Jr., Chicago, Ill., assignors to Pullman-Standard Car Manufacturing Company, Chicago, Ill., a corporation of Delaware

Application June 18, 1947, Serial No. 755,300

15 Claims. (Cl. 105—315)

1

This invention relates to railway sleeping cars of the type having a plurality of permanently independent rooms arranged for individual occupancy and disposed at upper and lower levels and accessible from a common passageway.

The principal object of the invention is realized in the provision of a railway car having room accommodations disposed at upper and lower levels, with windows in the side wall of the car individual to the respective rooms and disposed at a single level throughout the length of the car.

An important object of the invention lies in the provision of a railway car having individual accommodations disposed at upper and lower levels upon opposite sides of a common passageway, with windows in the respective car side walls individual to the respectively associated rooms and disposed on a single level throughout the length of the car and upon opposite sides of the car.

Another object of the invention is the provision of a railway sleeping car having convertible daytime and nighttime seating and sleeping accommodations at upper and lower levels in which the various facilities of the respective accommodations are disposed, and arranged to provide for windows at a single level throughout the length of the car.

The foregoing and other and more specific objects of the invention, and by means of which the principles of the invention are realized, are attained by the construction and arrangement illustrated in the accompanying drawings, in which

Fig. 1 is a general plan view of a portion of a railway sleeping car, constructed in accordance with the invention and showing a plurality of upper and lower level rooms disposed at opposite sides of a central longitudinal passageway, and illustrating the folding type beds in extended positions for nighttime occupancy;

Fig. 2 also is a general plan view of a portion of a railway sleeping car complementary to that illustrated in Fig. 1, but showing the individual rooms made up for daytime occupancy with a seat disposed alongside of a window in each room;

Fig. 3 is a general side elevational view of that portion of the car illustrated in Fig. 1, showing the arrangement of the windows in the side wall of the car at a single level and showing in dotted outline the disposition of the various rooms at upper and lower levels;

Fig. 4 is a similar view of the portion of the car complementary to that illustrated in Fig. 3 and corresponding to that shown in Fig. 2, and like

2

Fig. 3, showing the upper and lower level rooms in dotted lines as made up for daytime seating occupancy, and with the windows disposed all at one level;

5 Fig. 5 is a longitudinal sectional view through a lower and an adjoining upper room, taken on the line 5—5 of Fig. 7, showing the rooms made up for daytime occupancy, and clearly revealing the disposition of the noors at two levels and the windows of the respective rooms at a single level;

10 Fig. 6 is a view similar to Fig. 5, illustrating the same upper and lower rooms but made up for nighttime occupancy, with the seats folded to inoperative positions and the beds extended in 15 horizontal operative positions and in partial overlapping relation at upper and lower levels, with the windows for the two rooms on a single level;

Fig. 7 is a transverse sectional view through a lower room taken on the line 7—7 of Fig. 5, showing one side of the cross partition separating upper and lower rooms as it appears from the lower room side, and also showing the noor level of this room coincident with that of the central passageway; and

20 Fig. 8 is a similar view through an upper room taken on the line 8—8 of Fig. 5, showing the opposite side of the cross partition as it appears from the upper room side, and revealing the floor level of this room disposed above that of the central passageway.

25 Fig. 9 is a general plan view of a portion of a railway sleeping car, constructed in accordance with the invention and showing a plurality of upper and lower level rooms disposed at opposite sides of a central longitudinal passageway, and wherein the rooms have been disposed alternately at upper and lower levels and upon op-

30 posite sides of a central longitudinal passageway common to all of the rooms, but in all prior arrangements the disposition of the various room facilities in each room has been such that it was necessary also to arrange the windows in the side walls of the car alternately at upper and lower levels, corresponding with the respectively associated rooms. The present invention pro-

35 vides a multi-level sleeping car affording all of the facilities, convenience and privacy of cars of this type, and having all of the windows for the various rooms disposed at a single level, and accomplishes this by the arrangement and dis-

40 position of the various facilities in the individual rooms. The invention basically consists of a unit comprised of two rooms, including a lower and an upper, disposed between separating partitions defining the opposite limits of the unit, and having an intermediate dividing partition 45 between the upper and lower rooms and in which

two endwise foldable pre-made beds are pivotally mounted for hinged movement in opposite directions into the respective rooms, where they occupy partially overlapping horizontal positions at upper and lower levels.

In the drawings, 10 represents a railway sleeping car having side walls 11 and 12, body end walls 13 and 14, and a roof 15. At one end, the car is provided with a vestibule 16 having side entrance doors 17 and folding step and trap-door assemblies 18. A body end door 19 closes the vestibule off from the car body. A central longitudinal passageway 20 leads from this end door throughout the length of the car to a similar end door 21 at the opposite end of the car. At the vestibule end of the car, a porter's section 22, convertible for day or night occupancy, as covered in Patent No. 2,346,878 of April 18, 1944, is disposed at one side of the passageway, and a general toilet 23, together with locker space 24, is disposed at the opposite side thereof. At the opposite end of the car, lockers 25 are disposed upon opposite sides of the central passageway. As best shown in Figs. 3 and 4, the car body 10 is supported upon spaced trucks 26 in the customary manner.

The entire interior of the car body is utilized to the provision of sleeping rooms disposed alternately at upper and lower levels at respectively opposite sides of the passageway, as best indicated in Figs. 1 and 2, and since all of the lower rooms are of similar construction and arrangement, and all of the upper rooms are alike, it will be necessary only to describe a lower and an upper room which comprise a unit duplicated throughout the length of the car to provide alternating upper and lower rooms, and which is best shown in Figs. 5 and 6. As revealed in these views, it will be seen that each unit comprised of a lower and an upper room is disposed between separating partitions 30 at opposite ends thereof, with an intermediate dividing partition 35 between the rooms of each unit. All of these partitions are disposed transversely of the car and extend from the respective side walls 11 and 12 to longitudinally extending partitions 33 defining the central passageway 20, and whereas the partitions 33 separate adjoining two room units, the partitions 35 divide the units each into an upper and a lower room.

The floor level of each lower room is coincident with that of the passageway 20, as best indicated in Fig. 7. This room is equipped with the same facilities as the upper room, the more important items of which include an endwise foldable bed 36, an enclosed hopper 37, a folding washbasin 38 and a folding seat 39. The bed 36 is pivotally mounted at 40 for endwise folding movement into the dividing partition 35 and comprises a section of less than full bed length, disposed vertically in the inoperative position flush with the surface of the partition. The bed is secured in this closed position by means of spring pressed latches 41 disposed in the side walls of the bed recess 42, and which are engageable automatically with indented catches 43 in respective sides of the bed as the bed is moved to closed position. The latches are pressed from engagement with the catches, and the bed operated by means of an operating handle 44 which is provided with an eccentric and suitable connected push rods passing through the catches 43 to engage the latches 41 and press them from engagement with the catches. A safety latch 45 mounted upon the side wall of the room in the

path of the arc traversed by the catch 43 at this side is adapted to engage automatically with the catch during the closing movement of the bed to prevent accidental displacement of the bed in the event the latch 41 should accidentally not be fully engaged. The latch 45 is prevented from entering the catch 43 during the opening movement of the bed by holding the operating handle 44 in the release position until the bed passes the position of the latch. The bed locking and safety catch arrangement is as covered in co-pending application, Serial No. 671,481, filed May 22, 1946.

The folding seat 39 is disposed at that end of the room with the bed 36, adjacent the partition 35 and facing in the opposite direction toward partition 30. The backrest portion of the seat is pivotally mounted at 49 for folding movements between the upright seating position shown in Fig. 5 and the inverted position indicated in Fig. 6. The backrest is connected to the seat cushion for coincidental movement by means of pivotally associated brackets 50, so that as the backrest is moved to its inoperative position, the seat cushion will be shifted and lowered to permit the backrest to occupy a lower inverted position beneath the operative position of the bed. The seat cushion is supported upon a pair of two-level brackets 51 disposed at opposite sides thereof, and as the backrest is operated, the seat cushion is adapted to slide from the upper level, which constitutes the normal seating level, down the sloping portion of the brackets to the lower level, thus accommodating the inverted backrest at a level normally occupied by the seat cushion and thereby permitting the bed 36 to occupy a lower operative position, all as best shown in Fig. 6.

The seat 39 and the bed 36 are so disposed and arranged that when the bed is in operative position, the seat is inoperatively disposed, and when the seat is in operative position, the bed is disposed upright in the bed recess 42. When disposed in horizontal operative position, the bed is supported at the partition 30 on a fixed bed rest 52 and at the partition 35 by the pivot mounting 40 and extends continuously from the partition 30 to a point within the partition 35. The partition 35 is provided with a recess 53 of greater depth than the bed recess 42, and into which the foot portion of the bed is adapted to extend and which affords ample foot room for an occupant of the bed. The bed section 36 is of less than full bed length, but the mattress is of full length and extends into the recess 53 to provide a full length bed in the horizontal operative position. When the bed section 36 is disposed vertically in the bed recess 42, the mattress is adapted to fold in the recess 53, as indicated in Fig. 5.

The enclosed hopper 37 is arranged adjacent to the partition 35, between the seat 39 and the passageway partition 33, and is disposed substantially on a level with the seat cushion in the operative position thereof, as best shown in Fig. 7. The hopper is fully enclosed and provided with a hinged cover. The folding washbasin 38 for this room is disposed at the opposite side of the entrance door from the enclosed hopper, in the corner of the room formed by the partition 30 and the passageway partition. The washbasin is mounted in a corner cabinet which extends to the floor and conceals the plumbing for the basin. The basin and cabinet arrangement for the lower room is exactly like that for the upper room,

which will more fully hereinafter be described. The upper level rooms have the floor 57 disposed above the level of the lower room floor and of the passageway 20, and all contain the same facilities as the lower level rooms, including a folding bed 60 in the partition 35, an enclosed hopper 61, a folding washbasin 62, and a seat 63 which faces in the same direction as the seat 39 of the lower room. The bed is pivotally mounted in the dividing partition at 59 for endwise folding movement into a bed recess 58 provided therein, and like the lower room bed, comprises a rigid section of less than full bed length disposed vertically in the recess in the inoperative position and flush with the surface of the partition 35 in this room. The bed is retained in the vertical retracted position in the same manner as the bed 36, by means of spring pressed latches 41 in the side walls of the bed recess, and which automatically engage the indented catches 43 in respectively adjacent sides of the bed when the bed is moved to the retracted position. The same type of mechanism, 44, also is used for disengaging the latches from the catches during the opening operation of the bed, and a safety latch 45 similar to that used in the lower room is provided upon the side wall of the room to prevent accidental displacement of the bed in the event that the latch 43 is not securely engaged upon closing the bed, and which also is releasable by the mechanism 44 during the opening operation of the bed.

In this upper room, the folding seat 63 is disposed at that end of the room opposite the bed 60 adjacent to the partition 30 and facing toward the opposite partition 35 so that it faces in the same direction as the seat in the lower room, whereby all of the seats in the car face in one direction. In this seat arrangement the seat cushion is disposed in fixed position and does not move with the backrest, but the backrest portion is pivotally mounted at 64 for folding movements between the upright seating position indicated in Fig. 5 and the inverted position shown in Fig. 6. The backrest is mounted upon supporting brackets 65 for pivotal movement independently of the seat cushion, whereby it may be moved to its inoperative position overlying the seat cushion when it is desired to extend the bed to its horizontal operative position, which then overlies the inverted backrest and is supported upon the upholstered bed support 66 mounted upon the partition 30. The relationship of the bed 60 and the seat 63 is such that the seat is inoperative when the bed is disposed in horizontal operative position, and when the bed is disposed in the vertical inoperative position in the recess 58, the seat may be utilized in the normal operative position.

When arranged in horizontal operative position, the bed extends continuously from the partition 30 to a point within the partition 35 and disposed in partial overlapping relationship to the lower room bed 36 in the area of the dividing partition, as seen in Fig. 6. The partition 35 is provided with a recess 67 of greater depth than the bed recess 58, and into which the bed is adapted to extend and which affords ample space for utilization of a full length bed in the room. The recess 67 is of substantial height whereby the bed may be made up with the head portion thereof extending in the partition. The bed section 60 is of less than full bed length, but the mattress used is of full length and extends into the recess 67 so as to provide a full length bed in the horizontal operative position thereof. When the fold-

ing bed section 60 is disposed in the vertical retracted position within the recess 58, the mattress is adapted to fold in the recess 61, as shown in Fig. 5. Looking at this figure, it will be seen that the beds for the upper and lower rooms of each pair of rooms, as defined between the separating partitions 30, are disposed for endwise folding movements into respectively opposite sides of the dividing partition 35 so that the same type of bed is extendable from each side of the partition in opposite directions into the respective rooms to provide full length beds for the rooms disposed at upper and lower levels and overlapping in the zone of the partition.

10 The enclosed hopper 61 for the upper room, like the seat 63, also is arranged adjacent to the partition 30 between the seat and the passageway partition 33 and disposed substantially on a level with the seat cushion, and like the lower room hopper, is fully enclosed and provided with a hinged cover.

15 The folding washbasin 62 for this room is substantially identical with that used in the lower room, but unlike that arrangement, is disposed in the corner of the room formed by the partition 35 and the passageway partition at the opposite side of the room entrance from the enclosed hopper. The basin, as shown in Fig. 8, is pivotally mounted in a cabinet 70 which is disposed parallel to and against the passageway partition 33 in the corner by the dividing partition, and which is fully enclosed to the floor and houses a drain 71 into which the basin empties, and hot and cold water supply pipes. It is to be noted that in both the upper and lower rooms the basin arrangement is so located as to enable full utilization of the open floor area of the respective rooms in the use of the basins, whereby its use is rendered most convenient without the necessity of leaning or reaching over the seat or hopper for access to the basin.

20 The dividing partition 35, in addition to housing the folding beds for the respectively adjoining rooms, also affords luggage storage facilities for the rooms. In the upper room, the storage space 72 is disposed in the lower portion of the partition beneath the beds and at the floor level 57 of this room. As shown in Figs. 5 and 6, the floor 73 of the storage space is sloped downwardly toward the inner end of the space. In the lower room, the storage space 75 is disposed in the upper portion of the partition above the lower bed recess 42 and the recess 67 and behind the upper bed recess 58, as best indicated in Figs. 5 and 6.

25 Sliding doors are provided for all of the rooms affording complete privacy to the occupants. A door 76 is provided for each upper and each lower room and which is slidable into a pocket in the passageway partition alongside of the hopper in the respective rooms, as best shown in the plan views, Figs. 1 and 2. Baggage racks 79 also are provided for the rooms, mounted upon respectively opposite sides of the separating partition 30. Shoe lockers 77 and 78 are provided for the respective upper and lower rooms, which are disposed in opposite sides of the dividing partition 35 and which have access doors from the rooms and other doors affording access thereto from the passageway 20. The locker 77 for the upper room is disposed in the dividing partition adjacent to the floor 57 and inwardly of the cabinet 70 for the folding washbasin, as best shown in Fig. 8. The locker 78 for the lower room is disposed in the dividing partition above

the hopper 37, as best indicated in Fig. 7, at one side of the bed recess 42, and extends into the partition beyond the pocket for the sliding door 76 and is offset for communication with the passageway 20 through the partition 33. The lockers may be entered only from the respective rooms or from the passageway.

A window 80 is disposed in the side wall of each room in the car in a position where an occupant of the seat in any room will, in every instance, be seated alongside of the window, and looking at Figs. 3 and 4, it will be noted that all of the windows on each side are disposed at the same level throughout the length of the car, and as best shown by a comparison of Figs. 7 and 8, which are representative of lower and upper rooms respectively at either side of the car, it will be seen that the windows at opposite sides of the car also are at the same level—wherefore it may be said that all of the room windows of the car are disposed at one level. By the particular arrangement of the room facilities hereinbefore described, it is possible for the windows throughout the car to be disposed at a single level. The arrangement of beds of the same endwise folding type at opposite sides of the one partition dividing the two rooms and opening into the respective rooms in opposite directions while overlapping in the partition, enables such disposition of the beds, seats and floor levels as to make feasible the location of all windows at one level.

Applicants' arrangement affords a sleeping car of substantial passenger capacity having twenty-four fully private rooms convertible for day or night seating or sleeping accommodations and which capacity also is attributable to the arrangement of the beds both in the dividing partition, together with other facilities of the rooms, such as luggage space, shoe lockers and the like.

What is claimed is:

1. In a railway sleeping car having side walls, spaced passageway partitions defining a central longitudinal passageway, a plurality of rooms at each side of the passageway adapted severally for individual occupancy and disposed alternately at upper and lower levels, separating partitions extending between said side walls and the respective passageway partitions defining pairs of rooms each consisting of adjoining upper and lower rooms, dividing partitions disposed respectively between the rooms of each pair, a pair of endwise foldable bed panels each of less than full bed length disposed respectively substantially vertically within opposite faces of each dividing partition and pivotally mounted for movement in opposite directions to horizontal positions in the respective upper and lower rooms extending substantially from the opposite faces of said dividing partition to the respective separating partitions, bedding supported on said panels and extending into the dividing partition from opposite sides thereof in end overlapping relationship to provide full length beds in the respective rooms, a luggage compartment for the lower room disposed in the upper portion of the dividing partition, a luggage compartment for the upper room disposed in the lower portion of the dividing partition, a seat in each of the rooms and all facing in the same direction, and a window in each room disposed in the side wall alongside of said seat, all of said windows being disposed at substantially the same level throughout the length of said car and upon opposite sides thereof.

2. In a railway sleeping car having side walls, spaced passageway partitions defining a central longitudinal passageway, a plurality of rooms at each side of the passageway adapted severally for individual occupancy and disposed alternately at upper and lower levels, separating partitions extending between said side walls and the respective passageway partitions defining pairs of rooms each consisting of adjoining upper and lower rooms, dividing partitions disposed respectively between the rooms of each pair, a pair of endwise foldable bed panels each of less than full bed length disposed respectively substantially vertically within opposite faces of each dividing partition and pivotally mounted for movement in opposite directions to horizontal positions in the respective upper and lower rooms extending substantially from the opposite faces of said dividing partition to the respective separating partitions, bedding supported on said panels and extending into the dividing partition from opposite sides thereof in end overlapping relationship to provide full length beds in the respective rooms, a luggage compartment for one of the rooms disposed in the upper portion of the dividing partition and a luggage compartment for the other room disposed in the lower portion of the dividing partition, a seat in each of the rooms, and a window in each room disposed in the side wall alongside of said seat, and all of said windows being disposed at substantially the same level.

3. In a railway sleeping car having side walls, spaced passageway partitions defining a central longitudinal passageway, a plurality of rooms at each side of the passageway adapted severally for individual occupancy and disposed alternately at upper and lower levels, separating partitions extending between said side walls and the respective passageway partitions defining pairs of rooms each consisting of adjoining upper and lower rooms, dividing partitions disposed respectively between the rooms of each pair, a pair of endwise foldable bed panels each of less than full bed length disposed respectively substantially vertically within opposite faces of each dividing partition and pivotally mounted for movement in opposite directions to horizontal positions in the respective upper and lower rooms extending substantially from the opposite faces of said dividing partition to the respective separating partitions, bedding supported on said panels and extending into the dividing partition from opposite sides thereof in end overlapping relationship to provide full length beds in the respective rooms, a seat in each of the rooms, and a window in each room disposed in the side wall alongside of said seat, all of said windows being disposed at substantially the same level.

4. In a railway sleeping car having side walls, spaced passageway partitions defining a central longitudinal passageway, a plurality of rooms at each side of the passageway adapted severally for individual occupancy and disposed alternately at upper and lower levels, separating partitions extending between said side walls and the respective passageway partitions defining pairs of rooms each consisting of adjoining upper and lower rooms, dividing partitions disposed respectively between the rooms of each pair, a pair of endwise foldable bed panels each of less than full bed length disposed respectively substantially vertically within opposite faces of each dividing partition and pivotally mounted for movement in opposite directions to horizontal positions in the

respective upper and lower rooms extending substantially from the opposite faces of said dividing partition to the respective separating partitions, bedding supported on said panels and extending into the dividing partition from opposite sides thereof in end overlapping relationship to provide full length beds in the respective rooms, and a window in each room disposed in the side wall and all disposed at substantially the same level.

5. In a railway sleeping car having side walls, spaced passageway partitions defining a central longitudinal passageway, a plurality of rooms at each side of the passageway adapted severally for individual occupancy and disposed alternately at upper and lower levels, dividing partitions disposed respectively between adjoining upper and lower rooms, a pair of endwise foldable bed panels each of less than full bed length disposed respectively substantially vertically within opposite faces of each dividing partition and pivotally mounted for movement in opposite directions to horizontal positions in the respective upper and lower rooms defining substantially the length of each room, bedding supported on said panels and extending into the dividing partition from opposite sides thereof in end overlapping relationship to provide full length beds in the respective rooms, and a window in each room disposed in the side wall and all disposed at substantially the same level.

6. In a railway sleeping car having side walls, spaced passageway partitions defining a central longitudinal passageway, a plurality of rooms at each side of the passageway adapted severally for individual occupancy and disposed alternately at upper and lower levels, dividing partitions disposed respectively between adjoining upper and lower rooms, a pair of endwise foldable bed panels each of less than full bed length disposed respectively substantially vertically within opposite faces of each dividing partition and pivotally mounted for movement in opposite directions to horizontal positions in the respective upper and lower rooms defining substantially the length of each room, and bedding supported on said panels and extending into the dividing partition from opposite sides thereof in end overlapping relationship to provide full length beds in the respective rooms.

7. In a railway sleeping car having side walls, spaced passageway partitions defining a central longitudinal passageway, a plurality of rooms at each side of the passageway adapted severally for individual occupancy and disposed alternately at upper and lower levels, dividing partitions disposed respectively between adjoining upper and lower rooms, a pair of endwise foldable bed panels each of less than full bed length disposed respectively substantially vertically within opposite faces of each dividing partition and pivotally mounted for movement in opposite directions to horizontal positions in the respective upper and lower rooms defining substantially the length of each room, bedding supported on said panels and extending into the dividing partition from opposite sides thereof in end overlapping relationship to provide full length beds in the respective rooms, a luggage compartment for one of the rooms disposed in the upper portion of the dividing partition and a luggage compartment for the other room disposed in the lower portion of the dividing partition, and a window in each room disposed in the side wall and all disposed at substantially the same level.

8. In a railway sleeping car having side walls, spaced passageway partitions defining a central longitudinal passageway, a plurality of rooms at each side of the passageway adapted severally for individual occupancy and disposed alternately at upper and lower levels, separating partitions, extending between said side walls and the passageway partitions defining pairs of rooms upon respective sides of the passageway each consisting of adjoining upper and lower rooms, dividing partitions disposed respectively between the rooms of each pair, a pair of endwise foldable bed panels each of less than full bed length disposed respectively substantially vertically within opposite faces of each dividing partition and pivotally mounted for movement in opposite directions to horizontal positions in the respective upper and lower rooms extending substantially from the dividing partition to the respective separating partitions, bedding supported on said panels and extending into the dividing partition from opposite sides thereof in end overlapping relationship to provide full length beds in the respective rooms, a luggage compartment for one of the rooms disposed in the upper portion of the dividing partition and a luggage compartment for the other room disposed in the lower portion of the dividing partition, a seat in each of the rooms, and a window in each room disposed in the side wall alongside of said seats, all of said windows disposed at substantially the same level.

9. In a railway sleeping car having side walls, spaced passageway partitions defining a central longitudinal passageway, units each of two rooms between said respective partitions and the side walls adapted respectively for individual occupancy and disposed at upper and lower levels, partitions extending between said side walls and the passageway partitions defining opposite ends of said units, a dividing partition disposed between the upper and lower rooms of each unit, a pair of endwise foldable bed panels each of less than full bed length disposed respectively substantially vertically within opposite faces of the dividing partition and pivotally mounted for movement in respectively opposite directions to horizontal positions in the upper and lower rooms of each unit and extending substantially from the dividing partition to the respective end partitions, bedding supported on said panels and extending into the dividing partition from opposite sides thereof in end overlapping relationship to provide full length beds in the respective rooms, a luggage compartment for one of the rooms disposed in the upper portion of the dividing partition and a luggage compartment for the other room disposed in the lower portion of the dividing partition, a seat in each of the rooms, and a window in each room disposed in the side wall alongside of said seats, both of said windows being disposed substantially at the same level.

10. In a railway sleeping car having side walls, spaced passageway partitions defining a central longitudinal passageway, units each of two rooms between said respective partitions and the side walls adapted respectively for individual occupancy and disposed at upper and lower levels, partitions extending between said side walls and the passageway partitions defining opposite ends of said units, a dividing partition disposed between the upper and lower rooms of each unit, a pair of endwise foldable bed panels each of less than full bed length disposed respectively substantially vertically within opposite faces of the dividing partition and pivotally mounted for

11

movement in respectively opposite directions to horizontal positions in the upper and lower rooms of each unit and extending substantially from the dividing partition to the respective end partitions, bedding supported on said panels and extending into the dividing partition from opposite sides thereof in end overlapping relationship to provide full length beds in the respective rooms, a seat in each of the rooms, and a window in each room disposed in the side wall alongside of said seats, both of said windows being disposed substantially at the same level.

11. In a railway sleeping car having side walls, spaced passageway partitions defining a central longitudinal passageway, units each of two rooms between said respective partitions and the side walls adapted respectively for individual occupancy and disposed at upper and lower levels, partitions extending between said side walls and the passageway partitions defining opposite ends of said units, a dividing partition disposed between the upper and lower rooms of each unit, a pair of endwise foldable bed panels each of less than full bed length disposed respectively substantially vertically within opposite faces of the dividing partition and pivotally mounted for movement in respectively opposite directions to horizontal positions in the upper and lower rooms of each unit and extending substantially from the dividing partition to the respective end partitions, bedding supported on said panels and extending into the dividing partition from opposite sides thereof in end overlapping relationship to provide full length beds in the respective rooms, a luggage compartment for one of the rooms disposed in the upper portion of the dividing partition, and a luggage compartment for the other room disposed in the lower portion of the dividing partition.

12. In a railway sleeping car having side walls, spaced passageway partitions defining a central longitudinal passageway, units each of two rooms between said respective partitions and the side walls adapted respectively for individual occupancy and disposed at upper and lower levels, partitions extending between said side walls and the passageway partitions defining opposite ends of said units, a dividing partition disposed between the upper and lower rooms of each unit, a pair of endwise foldable bed panels each of less than full bed length disposed respectively substantially vertically within opposite faces of the dividing partition and pivotally mounted for movement in respectively opposite directions to horizontal positions in the upper and lower rooms of each unit and extending substantially from the dividing partition to the respective end partitions, and bedding supported on said panels and extending into the dividing partition from opposite sides thereof in end overlapping relationship to provide full length beds in the respective rooms.

13. In a railway sleeping car having side walls, spaced passageway partitions defining a central longitudinal passageway, units each of two rooms between said respective partitions and the side walls adapted respectively for individual occupancy disposed at upper and lower levels, a dividing partition disposed between the upper and lower rooms of each unit, a pair of endwise foldable bed panels each of less than full bed length disposed respectively substantially ver-

12

tically within opposite faces of the dividing partition and pivotally mounted for movement in opposite directions to horizontal positions in the

- 5 upper and lower rooms of each unit and defining substantially the length of said rooms, and bedding supported on said panels and extending into the dividing partition from opposite sides thereof in end overlapping relationship to provide full length beds in the respective rooms.

10 14. In a railway sleeping car having side walls, spaced passageway partitions defining a central longitudinal passageway, units each of two rooms between said respective partitions and the side walls adapted respectively for individual occupancy and disposed at upper and lower levels, a dividing partition disposed between the upper and lower rooms of each unit, a pair of endwise foldable bed panels each of less than full bed length disposed respectively substantially vertically within opposite faces of the dividing partition and pivotally mounted for movement in opposite directions to horizontal positions in the upper and lower rooms of each unit and defining substantially the length of said rooms, bedding supported on said panels and extending into the dividing partition from opposite sides thereof in end overlapping relationship to provide full length beds in the respective rooms, a luggage compartment for one of the rooms disposed in the upper portion of the dividing partition, and a luggage compartment for the other room disposed in the lower portion of the dividing partition, at least one of said beds extending into an intermediate portion of the dividing partition between said upper and lower compartments.

15 15. In a railway sleeping car having side walls, spaced passageway partitions defining a central longitudinal passageway, a unit comprising a pair of rooms between one of said partitions and the adjacent side wall, said rooms being disposed respectively at upper and lower levels and adapted for individual occupancy, a dividing partition between the upper and lower rooms, a pair of endwise foldable bed panels each of less than full bed length disposed vertically in respectively opposite faces of the dividing partition and pivotally mounted for movement in opposite directions to horizontal operative positions in the upper and lower rooms defining substantially the length of the respective rooms, and bedding supported on the respective panels extending into the dividing partition from opposite sides thereof to provide full length beds in the respective rooms.
